UNITED STATES PATENT OFFICE.

WALLACE N. OSBURN, OF NORTHLVILLE, AND FREDERICK H. RAGAN, OF DETROIT, MICHIGAN, ASSIGNORS TO GEMMER MANUFACTURING COMPANY, OF DETROIT, MICHIGAN, A CORPORATION OF MICHIGAN.

SPARK AND THROTTLE CONTROL.

Application filed June 12, 1922. Serial No. 567,674.

This invention relates to spark and throttle control assemblies and the invention consists in the structural features and arrangement of parts hereinafter described and illustrated in the accompanying drawings wherein:—

Figure 1 is an axial sectional view of the upper end of a steering column to which the improved assembly is applied;

Figure 2 is a transverse sectional view of the same;

Figure 3 is a perspective view of the control parts disassembled;

Figure 4 is a cross section on line 4—4 of Figure 1.

In these views the reference character 1 designates a steering post or column which may be rigidly mounted in the usual well known manner. 2, 2', 3 and 4 respectively 20 designate a steering shaft, a stationary shaft, a throttle control stem and a spark control stem all of which are tubular and disposed one within another and within the steering column, as is common practice. A steering 25 wheel 5 is mounted fast by any suitable means upon the upper end portion of the steering shaft. Just above said wheel there is mounted rigidly upon the stationary shaft 2' an annular flange 6 which rigidly carries a 30 pair of upstanding pins 7 oppositely arranged with respect to the axis of the steering column. Upon the flange 6 is seated a cap member 8 which covers the hub portion of the steering wheel and which has spaced 35 openings 8' that receive the pins 7. The stems 3 and 4 pass centrally through the cap member 8 and above the latter are provided with heads 9 which are diametrically elongated. Said heads respectively have 40 driving connection with a pair of rings 10 from which the throttle and spark control levers 11 project integrally. The preferred engagement between said rings and the heads 9 is of a quick detachable nature, the 45 rings being formed with diametrically opposed interior lugs 12 which are respectively notched, as indicated at 13, to accommodate the ends of the heads 9. The pins 7 pass through the outer portions of the central 50 openings of the rings 10 and form stops limiting rocking of said rings by engagement with the lugs 12. 14 is a plate forming a retainer for the rings 10, said plate

being adapted to seat upon shoulders 15 formed upon the upper end portions of the 55 pins 7, said pins being threaded above said shoulders for engagement by nuts 16 whereby the plate is clamped in the described position. Washers 17 formed of fiber or like material are arranged respectively between 60 the rings 10 and above and below said rings, said washers being held from rotation by engagement with the pins 7. It is preferred to form said washers each with an elongated central opening 18 of a shape corresponding 65 to that of the heads 9 so that said heads will form no obstacle to removal of the washers. A similarly shaped opening 19 in the cap member 8 permits the removal of the latter without disturbance of said heads. Said washers 70 provide bearing faces engaging the rings 10 against which faces the rings may bear with a predetermined pressure to oppose a desired resistance to turning of the spark and throttle control levers 11. The desired predetermined pressure is created by spring 75 tongues 20 which are struck out and downwardly deflected from a thin steel disk 21 which is disposed between the upper washer 17 and the retaining plate 14, said disk being 80 held against rotation by engagement with the pins 7.

The plate 14 is formed with an integral central upstanding collar 22 which is exteriorly threaded for engagement by an 85 annular metal insert 23 carried by a finishing plate 24 formed of hard rubber or other suitable material. Within the collar 22 there is disposed a metal cup member 25 through which passes an insulated portion of a conductor 26 extending axially through the steering column. At the end of said conductor there is soldered or otherwise electrically and mechanically secured a contact button 27 forming an abutment for the 90 lower end of the coiled spring 28. The upper end of said spring is received by and abuts against an inverted cup shaped member 29 which is inserted fixedly in a push button 30 formed of suitable insulating material and preferably marginally overhanging the finishing plate 24. The spring 28 normally maintains the switch element 29 normally slightly spaced above the complementary switch element 25 and contact between said elements may be established by a 100 105

- slight depression of the push button 30. A connection between said push button and the finishing plate 24 permitting the necessary slight movement while preventing disengagement is provided for by a split wire ring 31 which is engaged in an annular groove 32 formed in said push button, said ring projecting sufficiently from said groove to limit upward movement of the push button by engagement with the plate 24.
- One of the features of the described construction is the elimination of the serrated or other quadrants which commonly are associated with spark and throttle levers to hold them in adjustment, the present invention accomplishes this result by positioning a predetermined frictional resistance to rotation of said levers. A further desirable feature is the compact nature of the assembly and the provision for attachment and detachment of all the parts thereof without disturbing the heads carried by the upper ends of the throttle and spark control stems.
- Still another feature of the invention is the described push button switch for controlling the usual alarm signal, the spring 28 which maintains said switch normally open forming a part of the circuit when the switch is closed whereby the current flow is established from the terminal button 27 through said spring to the contact 29 and thence to the rim of the cup shaped contact 25, the latter being grounded through the disk 21, pins 7 and steering shaft 2. An insulating washer 33 is interposed between the terminal button 27 and the contact element 25.
- What we claim as our invention is:
1. A control assembly comprising a steering column, spark and throttle levers mounted to rotate upon said column, means including a plate above said levers for retaining said levers assembled upon the steering column, and spring means interposed between said plate and one of the levers opposing a predetermined resistance to rotation of said levers.
  2. A control assembly comprising a steering column, a lever mounted to rotate upon said column, and a disk mounted adjacent said lever having spring tongues subjecting the lever to a predetermined frictional resistance.
  3. A control assembly comprising a steering column, throttle and spark control levers mounted to rotate coaxially upon said column, retaining means for said levers, and a metal plate interposed between said levers and the retaining means and formed with struck out spring tongues subjecting both of said levers to a predetermined frictional resistance.
  4. A control assembly comprising a steering column, throttle and spark control levers mounted to rotate coaxially upon said column, each lever having a shoulder, and a pin fixedly mounted upon said column and forming a retaining element for said levers, said pin being engageable by said shoulders for limiting rotation of said levers.
  5. A control assembly comprising a steering column, throttle and spark control levers coaxially mounted to rotate upon said column, each lever having spaced projections, and a pair of pins rigidly carried by the steering column at opposite sides of the axis thereof and constituting abutments for said projections so as to limit rotation of said levers, and means engaging said pins above the levers to retain the latter upon the column.
  6. A control assembly comprising a steering column, throttle and spark control elements rotatable within said column, heads respectively carried by said elements at the upper end of the column, spark and throttle control levers having detachable actuating engagement with said heads, and a common means retaining said levers assembled upon the steering column and engaged with said heads.
  7. The combination with a steering column and a control element rotatable within said column, of a head carried by said element at the upper end of the column, a control lever having detachable actuating engagement with said head, a pin stationary upon the column extending through said lever, a projection on the lever engageable with the pin for limiting the rotation of said lever and retaining means for said lever engaging said pin.
  8. A control assembly comprising a steering column, a control element rotatable therewithin, a head carried by said element at the upper end of the column, a control lever for said element having a ring portion interiorly formed with opposed lugs notched for detachable engagement with said head, a pin stationary upon the steering column passing through said ring portion and forming a stop engageable by one of said lugs to limit rotation of the lever and retaining means for the lever engaging said pin.
  9. A control assembly comprising a steering column, a control element rotatable therewithin, an actuating member for said control element and a projection upon said actuating element having detachable actuating engagement with said control element and means coacting with said projection to limit rotation of said control element.
  10. In a control assembly, the combination with a stationary tube, a plurality of rings arranged in superposed relation upon said tube and having inwardly extending projections, levers connected to said rings for actuating the same, and means carried by the tube adapted to be engaged by said

- projections for limiting the movement of said levers.
11. A control assembly comprising a steering column, a lever mounted to rotate upon said column and a disk mounted adjacent said lever and means carried by said disk subjecting the lever to a predetermined frictional resistance.
12. A steering assembly comprising a steering column, a pair of levers mounted to rotate upon said column, and a non-rotative disk between said levers providing frictional resistance to rotation of said levers.
13. A steering assembly comprising a steering column, a pair of co-axial rotative rings mounted upon said column, actuating levers carried by said rings, control elements extending within the steering column actuatable by said rings respectively, a stationary ring between said rotative rings, and means carried by the column extending through said rings, holding the stationary ring from rotation and further limiting rotation of the rotative rings.
14. A steering assembly comprising a steering column, a pair of rings mounted coaxially and rotatively upon said column, members extending within said column actuatable respectively by said rings, a pair of pins carried by the column and projecting freely through said rings and a disk between said rings, held stationary by engagement with said pins.
15. A steering assembly comprising a steering column, rings mounted to rotate on said column, a pair of pins carried by the column and projecting freely through said rings, actuating levers carried by said rings, members extending within the column detachably engaged by and actuatable by said rings, and a disk between said rings held stationary by engagement with said pins and providing frictional resistance to rotation of said rings.
16. A steering assembly comprising a steering column, a pair of rings mounted co-axially and rotatively upon the column, actuating levers carried by said rings and a pair of pins carried by the column projecting through said rings and engageable by the rings to limit rotation of the latter.
17. A steering assembly comprising a steering column, a control member extending within said column, a head upon said control member, and an actuating element for said control member having a recess detachably receiving said head.
18. A steering assembly comprising a steering column, a control member extending through said column, a head upon said control member, and a lever having a ring portion rotatively mounted upon the column said ring portion having recesses at spaced points thereof detachably receiving said head.
19. A steering assembly comprising a steering column, a control member extending within said column, a head upon said control member, a ring rotatively mounted upon the column and having its inner periphery notched for detachable and actuating engagement with said head, and an actuating lever carried by said ring.
20. A steering assembly comprising spaced rotative rings having a common axis and provided with independent finger levers, the inner peripheries of said rings being notched, means for directing the rings in their rotary movement, concentric rotary members at the axis of the rings and heads upon said concentric members loosely received within the notches of the respective rings.
21. A steering assembly comprising a rotary member, an actuating lever carried thereby, members engaging both faces of the rotary member and cooperating therewith to direct the rotary member in its movements, a fastening element connecting the said members to each other, locking means for the fastening element, a removable cap piece, and an actuated member arranged at the axis of the rotary member and operatively connected thereto.
22. A motor vehicle control including a rotary member provided with a finger piece, members engaging both faces of the rotary member and co-operating therewith to direct the rotary member in its movements, a fastening element connecting the said members to each other, locking means for the fastening member, a removable cap piece holding the locking member in position, and an actuated member arranged at the axis of the rotary member and operatively connected thereto.
23. A motor vehicle control including a rotary member provided with a finger piece, an actuated tube at the axis of the rotary member and operatively connected therewith, guide means for the rotary member including a cap piece, a button mounted upon the cap piece, a conduit extending through the actuated tube and opposed contacts operatively connected to the conduit and button.
24. A motor vehicle control including a plurality of spaced superposed rotary members concentrically arranged and having independent finger pieces, guide means for the rotary members, concentric actuated tubes arranged at the axis of the rotary members and operatively connected thereto, a cap piece applied to one of the guide members, a button mounted upon the cap piece and arranged opposite the ends of the concentric actuated tubes, an electric cable extending through the said tubes, and contact means actuated by the button for controlling the electric circuit.
25. A motor vehicle control including a

- rotary control member provided with a finger piece, guide means engaging the control member to direct the rotary movements thereof and including a threaded plate, a 5 cap member screwed upon the threaded plate, a tubular actuated member arranged at the axis of the control member and operatively connected thereto, an electric cable extending through the tubular member, a 10 button mounted upon the cap member opposite the end of the tubular actuated member, and contact means actuated by the button for controlling the electric circuit.
26. In a control assembly, the combination 15 with a steering column, and a plurality of control members projecting upwardly from said column, of a pair of plates anchored and arranged in superposed relation upon said column, the opposed faces of said plates 20 being spaced apart throughout their entire area whereby a continuous space of substantially even depth is provided between said plates about said control members, and levers having portions arranged in superposed relation in the space between said plates and 25 respectively secured to said control members.
27. In a steering wheel assembly, a steering column, a stationary shaft in the column 30 having a lateral flange at its upper end, vertically spaced plates above said flange, a pair of rotatable control levers arranged in superposed relation between said plates, and bolts holding said levers between said plates 35 and holding the latter on the flange of said stationary shaft.
28. In a control assembly, the combination 40 with a steering column, and a plurality of control members projecting upwardly from said column, of vertically spaced plates anchored on said column, a pair of rotatable control levers having portions arranged in superposed relation between said plates and 45 respectively secured to said members, and a member anchored on said column between said plates providing frictional resistance to rotation of said levers, the arrangement being such that one lever may be moved without moving the other.
- 50 29. A control assembly comprising a steering column having a steering wheel there-
- on, vertically spaced plates above said column and wheel, a plurality of control levers having annular portions filling the space between said plates, a disk intermediate the annular portions of said control levers in frictional contact therewith, and means within the annular portions of said control members for holding said disk and plates from rotation. 60
30. In a control assembly, the combination with a steering column, and a plurality of control members projecting upwardly from said column, of rotatable rings respectively secured to said members, and a non-rotative 65 disk between said members providing frictional resistance to rotation of said members. 65
31. A control assembly comprising a rotary steering tube, a plurality of rotary control members and a fixed member concentrically arranged within said steering tube, superposed annular members respectively attached to said rotary control members, and a member interposed between said annular 70 members in frictional contact with the adjacent faces thereof anchored to said fixed member. 75
32. A control assembly comprising a rotary steering tube, a plurality of rotary control members in said tube, a fixed tube in said steering tube, superposed annular members respectively attached to said rotary control members, a member interposed between said annular members in frictional 80 contact with the adjacent faces thereof anchored to said fixed tube, and resilient means pressing said annular members against said friction member. 85
33. A control assembly comprising a rotary steering tube, a plurality of rotary control members in said tube, a fixed tube in said steering tube, superposed annular members respectively connected to said rotary control members, and a series of friction 90 members engaging the opposite faces of said annular members and anchored to said fixed tube. 95

In testimony whereof we affix our signatures.
